UNITED STATES PATENT OFFICE.

SAMUEL M. NELSON, OF HOVLAND, MINNESOTA.

CLOTHES-RACK.

1,103,997.

Specification of Letters Patent. Patented July 21, 1914.

Application filed April 11, 1913. Serial No. 760,439.

To all whom it may concern:

Be it known that I, SAMUEL M. NELSON, a citizen of the United States, residing at Hovland, in the county of Cook and State 5 of Minnesota, have invented certain new and useful Improvements in Clothes-Racks, of which the following is a specification.

This invention relates to clothes racks and more particularly to that class which may 10 be readily collapsed thereby adapting the same for convenient use with travelers, etc.

An object of this invention is the provision of a plurality of telescoping sections suitably arranged so that the same may be 15 secured to any suitable support and when the same is secured to a support the weight of itself will hold it in open position thereby eliminating the use of hooks and keepers of various types as has heretofore been used 20 in devices of this character.

Other objects as well as the nature, characteristic features and scope of my invention will be more readily understood from the following description taken in connection with the accompanying drawings and 25 pointed out in the claim forming a part of this specification wherein:—

Figure 1 is a side elevational view of my improved device showing the sections in 30 open position; Fig. 2 is an end view of the same; Fig. 3 is a cross sectional view of the tubular end members when in a folded position; and Fig. 4 is a detail perspective view of one of the side arms.

In the drawings is shown a plurality of 35 telescoping sections each of which is provided with tubular end members 5 having cross arms 6 suitably arranged therebetween and each of said cross arms being provided 40 with a multiplicity of detachable studs 7 which are adapted for supporting articles of various types. The uppermost of said sections has a cross arm 8 secured to the upper extremity of its tubular end members, 45 this also being provided with a multiplicity of detachable stud members 7 the same as in the other cross arms, and is further provided with a plurality of ears 9 in which

are formed openings so that the same may be secured to a suitable support through the 50 medium of a nail, etc., and when suspended in this manner the sections will be in an open position as shown to advantage in Fig. 1. A pair of side arms 10 are carried by the uppermost section in close proximity to 55 the cross arm 8 the same being pivotally mounted thereon so as to be conveniently folded inwardly when the rack is desired to be entirely collapsed.

This rack is made of any suitable material 60 preferably aluminum thereby forming a comparatively light device which may be conveniently carried in a suit case, trunk, etc., and having the studs 7 detachable so that the same may be readily removed when 65 it is desired to pack the same for shipment, etc., making a relatively flat device.

It will be understood that the above description and accompanying drawings comprehend only the general and preferred embodiment of my invention and that various minor changes in details of construction, proportion and arrangement of the parts may be made within the scope of the appended claim and without sacrificing any of 75 the advantages of my invention.

Having thus fully described my invention what I claim as new and desire to secure by Letters Patent is:—

A rack comprising a frame having side 80 bars, suspending means for said frame to support the same in a vertical plane, and secondary frames having side bars telescoping into each other and into the side bars of said first frame, said secondary frames 85 being adapted to drop into extended position upon suspension of said first frame, and clothes supporting pins carried by each frame.

In testimony whereof I affix my signature 90 in presence of two witnesses.

SAMUEL M. NELSON.
